(57) **CLAIM**

The ornamental design for a dog harness, as shown and described.

DESCRIPTION

FIG. 1 is a top perspective view of a dog harness showing my new design in a first configuration;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is a bottom perspective view of the dog harness of FIG. 1, shown in a second configuration; and,

FIG. 10 is an enlarged view of a detail of the dog harness, identified in FIG. 2.

In the drawings, the broken lines depict portions of the dog harness that form no part of the claimed design.
